CLAIM

The ornamental design for handpiece for wax shaping tool, as shown and described.

DESCRIPTION

FIG. 1 is a top, front and right-side perspective view of a hand piece for wax shaping tool showing my new design;

FIG. 2 is a right side elevational view, the left side view being a mirror image;

FIG. 3 is a top plan view;

FIG. 4 is a bottom plan view;

FIG. 5 is a front elevational view;

FIG. 6 is a rear elevational view;

FIG. 7 is a cross-sectional view as taken from line 7—7 of FIG. 2; and,

FIG. 8 is a cross-sectional view as taken from line 8—8 of FIG. 2.

The broken-line showings of FIGS. 1 and 2 are environmental only and form no part of the claimed design.

FIG. 1

FIG. 3FIG. 5FIG. 2FIG. 6FIG. 7FIG. 4FIG. 8
